US00D757465S

(12) **United States Design Patent**
Woelfel et al.

(10) **Patent No.:** **US D757,465 S**
(b4) **Date of Patent:** **** May 31, 2016**

(54) **COLOR CENTER DISPLAY**

(71) Applicant: **BEHR PROCESS CORPORATION**,
Santa Ana, CA (US)

(72) Inventors: **Erika Woelfel**, Irvine, CA (US); **Sarah Furnari**, Costa Mesa, CA (US); **Mark Germain**, Long Beach, CA (US); **Amy Tow Harmon**, Huntington Beach, CA (US); **Joel Barenbrugge**, Naperville, IL (US); **Michael J. Ebert**, Genoa, IL (US); **Thomas E. Hubley**, Fox River Grove, IL (US); **Jeffrey B. Fridrich**, Chicago, IL (US)

(73) Assignee: **Behr Process Corporation**, Santa Ana, CA (US)

(**) Term: **14 Years**

(21) Appl. No.: **29/476,927**

(22) Filed: **Dec. 18, 2013**

(51) LOC (10) Cl. **06-04**

(52) U.S. Cl.

USPC **D6/672**

(57) **CLAIM**

The ornamental design for a color center display, as shown and described.

DESCRIPTION

FIG. 1 is a front perspective view thereof;

FIG. 2 is an alternate perspective view thereof; and,

FIG. 3 is a front elevational view thereof.

The broken-line disclosure in the views represents portions of the color center display in which the claimed design is embodied, but which form no part of the claimed design.

1 Claim, 3 Drawing Sheets
